(57) **CLAIM**

The ornamental design for decorator receptacles, as shown and described.

DESCRIPTION

FIG. 1 is a front, bottom and right side perspective view of the design.

FIG. 2 is a front view thereof.

FIG. 3 is a right side view thereof.

FIG. 4 is a left side view thereof.

FIG. 5 is a top plan view thereof.

FIG. 6 is a bottom plan view thereof.

FIG. 7 is a front, bottom and right side perspective view of the design in combination with a wall plate.

FIG. 8 is a front view of an alternative embodiment of the design; and,

FIG. 9 is a front view of another alternative embodiment of the design.

In all of the views, the broken lines are for environmental purposes only and form no part of the claimed design. The rear is not part of the claimed design.
